THERMOSTATIC ASH TRAY

Waldemar Ayres, New York, N. Y.

Application June 29, 1936, Serial No. 87,992

8 Claims. (Cl. 131—240)

This invention relates to devices for supporting smoking articles such as cigars, cigarettes and the like, and particularly to devices of the type commonly known as ash trays.

5 Ash trays are and have been for many years past a common article of commerce and in wide use. These have been made in many designs and widely varying constructions, but in these prior constructions the cigarette or other smoking article has been supported upon a stationary support; and this fact has resulted always in certain inherent disadvantages which have caused great annoyance and even property damage. In particular it frequently happens that a cigarette laid 10 on the support is forgotten while the smoker is engaged in some other activity and, before he returns to pick up the cigarette or to put it out, it may have burned back for an inch or more with a consequent shifting of its center of gravity toward unburned end. If the cigarette has been left with an end projecting this shift in its center of gravity may, and frequently does, result in the cigarette toppling off from the support and a burning of the table or rug or other 15 furniture. The property damage inadvertently caused in this way is estimated at several hundreds of thousands of dollars annually.

Frequently cigarettes are extinguished by the 20 heat absorption of the support. Often such cigarettes are only partly burned up and the remainder is wasted in consequence.

Even if the cigarette continues to burn and does not burn so far as to fall off the support, the 25 fumes from the burning end passing back through the unburned portion of the cigarette tend to condense upon the part of the cigarette which is in contact with the relatively cold support, and as a consequence when the cigarette is picked up, it is found that the part which has 30 been in contact with the support is soaked and stained with the condensate. The cigarette in this condition is unsightly and distasteful to many persons, so that frequently it is thrown 35 away and the greater part of the cigarette thus wasted. Or, if it is not thrown away, the burning zone creeps ahead along the top side of the cigarette and when smoked often burns across behind that portion in which condensation has 40 occurred. The unburned portion, of course, has not dropped off from the cigarette when the smoker tapped away the ash, and as a consequence when the cigarette burns across behind the unburned zone the latter part is left still 45 burning without support and frequently drops 50 55

onto the smoker's clothes causing a burn or at best the soiling of clothes with ashes.

Because of these recognized unsatisfactory features of the ordinary ash tray many attempts have been made to design ash trays so as to 5 extinguish the cigarette or other smoking article after it has burned for a limited time on the tray. This, however, has not been accepted as a solution, and is found generally unsatisfactory because the smoker wants to find his cigarette 10 lighted and ready for smoking when he picks it up from the tray. It is a source of continual annoyance to find that the cigarette has been automatically extinguished and ash trays which cause this annoyance cannot be generally acceptable. 15

Accordingly, it is an object of my invention to provide an ash tray which, while allowing the smoking article to burn freely, will always keep the burning portion of the smoking article over the receptacle intended for the ashes and will prevent the burning stub from falling off the support in any direction except into said receptacle. 20

Another object of my invention is to prevent the unsightly and undesirable condensation of 25 vapors and consequent staining of the smoking article.

Another object of my invention is to prevent the extinguishing of the burning in the smoking article until it has burned almost to the end thereof. 30

With these and other objects in view, my invention contemplates an ash tray having a movable support for feeding the smoking article toward the ash receptacle part of the tray, and especially with means for moving the smoking article on the support in response to an increase of the temperature adjacent the support which results from the burning of the article. For this purpose I may advantageously use the thermal energy developed by burning of the article either for controlling the movement of the support or, advantageously, to provide the motive power for driving the support. 35 40 45

The simplest way of accomplishing this is to provide a bi-metallic thermostatic element adjacent and slightly beyond and above the support so as to be beside the cigarette and responsive to its temperature as the burning part approaches the support. Such a thermostat can be connected directly to the movable support so that, as the cigarette burns toward the thermostat, its temperature is increased, the movable support is operated, and the cigarette is moved 50 55 60

to keep its burning portion approximately in a constant position over the ash receptacle.

In the accompanying drawings I have shown several preferred embodiments of my invention and certain modifications thereof. I have chosen these with a view to explaining the invention and the principles thereof and the best manner of embodying the same. These and the following specification and descriptions are not intended to be exhaustive nor limiting, but on the contrary it is my intention to enable others skilled in the art to adapt and modify the invention and to construct it in such various forms as may be best adapted for the requirements of any particular conditions.

In the drawings:

Fig. 1 is a fragmentary view in vertical section of an ash tray with a support embodying my present invention.

Fig. 2 is a similar view on an enlarged scale showing the movement of a cigarette by operation of the thermostat and the movable support.

Fig. 3 is a fragmentary view in side elevation of the same device as shown in Figs. 1 and 2.

Fig. 4 is a view in plan, partially broken away, of the same device.

Figs. 5 to 7 inclusive show an ash tray with a modified support and thermostatic feeding device.

Fig. 6 is a transverse sectional view taken on line 6—6 of Fig. 7; and Figs. 5 and 7 are longitudinal sectional views taken respectively on lines 5—5 and 7—7 of Fig. 6.

Fig. 8 is a sectional view similar to Fig. 1 showing another modified thermostatic feeding device.

Fig. 9 is a sectional view similar to Fig. 5 showing still another modification.

Figs. 10 and 11 are views, respectively in section and plan, of another embodiment of my device, the section of Fig. 10 being taken on line 10—10 of Fig. 11.

Fig. 12 is a view similar to Fig. 10 showing still another embodiment of my invention.

Referring first to Figs. 1 to 4 inclusive, I have shown therein a portion of an ash ray 15 of conventional shape. Instead of the usual semi-cylindrical depression in the edge for supporting a cigarette directly, I have provided a depressed portion 16 with substantially parallel sides, in which the feeding and supporting device of my invention is engaged frictionally or by any suitable securing means of which screws, spot-welding, snap springs, etc., are examples.

The feeding and supporting device in this case includes a frame 17 of U-shape, coiled bimetallic thermostatic elements 18 secured at their centers to the sides of the frame 17 above the edge of the ash receptacle 15, and beyond the thermostats 18 and mounted between the sides of the frame 17, conveyor rolls 19, on which a cigarette or other smoking article 20 may rest.

The axles 21 of the rolls 19 between the rolls themselves and their bearings in the frame 17 serve as sheaves for the frictional engagement of a driving cord 22 which, for example, may be a heavy silk thread or a fine silk cord. For this purpose the axles 21 are preferably made concave in the area where the driving cord is to encircle them.

The cord 22 is connected at one end to the free end of the thermostat 18 and at its opposite end is connected to a spring 23 which serves to keep the cord under tension and thereby to maintain a frictional engagement with the axle

21 and also to retract the cord and the rolls 19 when the thermostat is cooled. The rolls 19 are shown concave in order to hold the smoking article approximately centered on them and positioned laterally with respect to the thermostats. This, however, is not essential especially if the sides of the frame 17 are made sufficiently high to hold the article on the rollers and spaced laterally from the thermostats.

In the operation of this device, the cigarette 20 is placed upon the rolls 19 exactly as it would be placed on any ordinary ash tray, that is to say with the burning portion 25 projecting over the ash receptacle 15. As the cigarette burns back in this position the burning portion 25 approaches the thermostatic element 18 and the latter is, therefore, gradually heated by radiation from the burning end of the cigarette. As the thermostat 18 is heated it tends to uncoil and its free end is moved toward the receptacle 15 pulling with it the driving cord 22. Since the latter is coiled around the axles 21 of the rollers 19, its movement rotates the rollers and thereby feeds the cigarette forward over the rollers until the burning portion 25 has been moved farther away from the thermostat 18 and the latter, therefore, ceases to increase in temperature. This position will be maintained or even retracted by cooling of the thermostat until the burning of the cigarette has brought its burning end again close to the thermostat 18, whereupon a further increase in temperature will repeat the operation and the cigarette will be moved again. This continues until the center of gravity of the cigarette moves beyond the center of the last roll 19, at which time the cigarette butt topples into the ash receptacle 15. When this occurs, however, the thermostat 18 will have been already extended to a substantial degree so that its temperature will be considerably higher than in the position shown, for example, in Fig. 2. Consequently, during the last movement of the cigarette the burning portion will be farther back with respect to the thermostat 18 than when the initial movement took place. Thus, as the center of gravity of the cigarette moves forward, the length of the cigarette which projects beyond the rollers 19 is shortened; and thus the butt may be supported as long as there is enough left to be comfortably smoked. When it burns farther it falls into the tray.

The thread 22 in this case is illustrative of any drive transmitting device between the thermostatic element 18 and the rollers 19. Obviously, a frictional bar or a gear rack or sprocket chain or a conveyor belt over the rolls and numerous other devices well known in the art for this purpose could be used; but the cord has the great advantage that it is simple, inexpensive and entirely fool-proof. The conveyor belt shown at 26 in Fig. 10 has the advantage that it covers the mechanism and the rolls and prevents dirt from collecting between the rolls. The belt is preferably a fabric of fine wire woven or spiral or chain link or braided, etc.

Similarly, the coiled bimetallic strip 18 is representative of numerous types of thermostatic elements any of which could be used for the purposes of my invention. The use and operation of such thermostatic elements is already generally well understood in the art and will need no further discussion here.

The amplitude of the thermostat 18, which in the case of a coiled bimetallic strip is dependent upon the metals used, the thickness of each

metal in the strip and the length of the strip, should, of course, be sufficient to feed a cigarette substantially its full length and off the conveyor into the tray. In practice, however, it 5 may frequently happen that a cigarette after being fed a part of its length may be picked up and smoked, whereupon another cigarette only just lighted may be dropped in its place on the ash tray before the thermostat 18 has had sufficient time to return to its starting position 10 by cooling. For this reason it has been found in practice that the thermostat 18 should be designed with an amplitude sufficient to operate the rollers 19 for feeding a cigarette a distance 15 equal to several times its length. It has been found in practice that two or three times its length gives an adequate safety factor. This is not difficult to accomplish because the load on the rollers is so small and the power of the thermostat 20 may easily be made so large as compared thereto that the diameter of the sheaves on the axles 21 may give a very large ratio of movement of the periphery of the rollers as compared with that of the free end of the thermostat.

25 In Figs. 5, 6 and 7, I have shown a feeding and supporting mechanism designed to move the cigarette step-by-step. In this case the tray 15a is formed with a receptacle 16a, substantially similar to that shown in Figs. 1 to 4 inclusive. The frame 17a in this case is made with flared upper edges so that the cigarette or other smoking article is supported directly upon the flared sides, and for this reason obviously the lower part of the frame 17a is narrower than 30 is shown in Figs. 1 to 4. Within the frame 17a is a carrier rack 19a which is movable up and down and forward and back within a range limited by the pin 30 extending laterally from the rack 19a into the slot 31 in the frame 17a.

40 The thermostatic element 18a in this case is mounted upon a rocking pivot 33, instead of upon a fixed pivot as in Figs. 1 to 4 and its outer end is anchored at 34. The thermostat is connected through the pivot 33 and the spring arm 35 to the rack 19a which it engages by means of the pins 36 and 37. A cam finger 38 extended from the rear of the spring arm 35 serves to lift the rack 19a when the spring arm 35 snaps forward, and thereby to engage the cigarette 20 upon, and to move it forward with the rack.

The projection 39 on the bottom of the frame 17a serves to restrain the movement of the arm 35 until sufficient force has been accumulated in the thermostat 18a to flex the spring arm 35 and snap it over the projection 39. Thus the movement of the cigarette is step-by-step and the amplitude of each step, which depends upon the height of the projection 39 and the thickness of the spring 35, is regulated so that at 45 each step the cigarette is moved so far that the thermostatic element 18a may cool enough to snap the arm 35 back over the projection 39 before the burning end again approaches the thermostat so closely as to operate it again in the forward direction.

To facilitate the resetting of the arm 35 it may be made of light easily flexed spring strip with a reinforcing strip enough shorter to clear the projection 39. On the forward stroke the reinforcing strip restrains the flexing of the lighter strip and requires a greater force to jump the projection 39 than will suffice to reset the device upon cooling. Another device for this same purpose is shown in Fig. 9 where a snap 75 pawl 48 yields freely on the return stroke but

holds against the projection 39c on the forward stroke until the arm 35c is flexed enough to lift it over the projection.

Since, in this case the conveyor rack cannot operate a second time until it has been reset by 5 cooling of the thermostat, it is essential that the design should be such as to allow such cooling in every case. In order to avoid having a second cigarette laid with its burning portion next to the thermostat immediately after it has operated 10 upon another cigarette, the thermostat 18a is placed sufficiently far back relative to the supporting frame 17a and the latter is made sufficiently short so that any cigarette laid upon it normally would project beyond the thermostat 15 and allow it time to cool.

If the support flanges 17a and the rack 19a are provided with fine projections tilted forward toward the tray, these provide a ratchet effect on the cigarette itself and the thermostat may 20 then be connected directly to the rack 19a without provision for lifting and lowering the rack. For this purpose I may use a ribbon of fabric similar to a plush or pile fabric but preferably made of very fine wires. 25

In Fig. 8, I have shown a device quite similar to that of Figs. 5 to 7. In this case, however, the spring arm 35 does not act directly on the conveyor rack 19b, but instead an arm 40 is secured to the pivot 33 and is connected through 30 the link 41 to the conveyor rack 19b. The thermostat 18b in this case is reversed as compared with Fig. 5 so that it operates in the opposite direction.

In the operation of this device, heat from the 35 burning portion of the cigarette tends to uncoil the thermostat 18b. This tendency, however, is at first restrained by the engagement of the spring arm 35b on the projection 39b until a substantial force has accumulated sufficient to 40 snap the spring 35b over the projection 39b. When this occurs the arm 40, through the link 41, lifts the rack 19b into engagement with the cigarette 20 and carries it forward a distance sufficient to permit cooling of the thermostat 18b 45 while the cigarette is burning back across the distance of its movement.

In this case, as in the case illustrated in Figs. 5 to 7, the spring arm 35 is preferably laminated with one relatively light spring extending into 50 engagement with the projection 39 and another reinforcing spring behind the first on the side opposite to the projection 39 when the thermostat is retracted, or a pawl may be used on the end of the spring arm 35 which hinges freely to 55 slide over the projection 39 on the return stroke but engages on the forward stroke, as shown for example in Fig. 9.

In Fig. 9, I have shown another device similar to those of Figs. 5 and 8. In this case the 60 rack 19c is made with gear teeth on its bottom edge which engage through a gear 44 with the arbor shaft 45. A gear wheel 46 is secured to the pivot 33 and also meshes with pinion 44 on the arbor shaft. 65

The shaft 45 has its end pivot engaged in the arcuate slots 47 and is free to rise or fall in the slots. The arm 35c operating over the projection 39c in the bottom of the ash receptacle 15c serves the same purpose and in substantially the 70 same way as the arms 35 and 35b on the projections 39 and 39b in Figs. 5 and 8.

In the operation of this device the heating of the thermostat builds up a force against the spring arm 35c. When this is sufficient to permit 75

it to pass over the projection 39c the sudden drive of the gear wheel 46 against the arbor shaft 45 raises the latter to the top of the slot 47 thereby raising the rack 19b into engagement 5 with the cigarette 20. As soon as the arbor shaft 45 strikes the upper ends of the guide slots 47, so that it can no longer rise, the driving motion is transmitted through the arbor shaft to the rack 19c and the cigarette 20 is, therefore, moved 10 forward to the end of the thermostat stroke. At the end of the stroke the arbor shaft 45 and the rack 19c drop again to the bottom of the slot 47, the cigarette 20 is released, and upon cooling of the thermostat 18c the rack 19c is returned to 15 its first position.

In Figs. 10 and 11, I have shown another embodiment of my invention combining certain features of both the continuous drive type, shown in Figs. 1 to 4 inclusive, and the step-by-step type, shown in Figs. 5 to 9 inclusive. In this case a gear train is used instead of the driving cord 22, a gear 50 meshing with the gear 51 on the roll 19d which in turn drives the gear 52 on the other roll 19d through an intermediate gear 53. The thermostat 18d in this case is fixed at the pivot 33d and its free end is bent over as shown at 54 to form a spring pawl engaging the teeth of the gear 50.

As thus far described, this device would operate 30 in precisely the same way as that described in Figs. 1 to 4, the thermostat 18d simply operating through the pawl 54 and the gear chain 50, 51, 52, 53 instead of through the cord 22. In the case illustrated in Figs. 10 and 11, however, I have provided a detent pawl 55 which may, for example, be simply a spring strip operating 35 against the teeth of the gear wheel 50 to prevent return movement. This has the advantage that if when the thermostat is hot the burning portion of the cigarette either when first laid down or by reason of operation of the conveyor rolls 19d should be extended beyond the position adjacent the thermostat 18d, the latter could cool 40 without moving the burning portion back closer to itself and thus an increased cooling period would be allowed, as compared with the construction of Figs. 1 to 4 inclusive. During this cooling period the pawl 54 would move back over the teeth of the gear whel 50, and thus a substantial 45 resetting of the thermostat would occur. With this arrangement a lesser factor of safety is required in determining the amplitude of maximum operation.

The device shown in Fig. 12 is a step-by-step ratchet device similar in the principle of its operation to the devices shown in Figs. 5 to 9 inclusive, but with the advantage as compared with those figures that it is possible for the ratchet to 50 operate several steps forward before resetting.

In the construction shown in Fig. 12, the end 55 of the thermostat 18e is provided with a ratchet pawl 54e which engages the teeth of a ratchet wheel 60 on the end of the shaft 21e of the conveyor roll 19e. The shaft 21e of the other conveyor roll is positioned in a slot 61 so that it is permitted a slight vertical movement. Between and slightly below the center of the rolls 65 19e is positioned a friction roll 63 mounted with its pivots in horizontal slots so that it in part supports the weight of one roll 19e and is crowded thereby into frictional engagement with the other roll as well so as to transmit rotary motion from one to the other.

70 75 In the operation of this device the heating of

the thermostat 18e pulls the pawl 54e against the teeth of the ratchet wheel 60 until it has gathered sufficient force to move a tooth past the detent pawl 55e. When this occurs the rolls 19e are rotated through an arc sufficient to move the cigarette beyond the thermostat 18e whereby to permit cooling of the thermostat and resetting of the pawl 54e to another tooth of the ratchet 60. If, however, for any reason resetting should not occur, the pawl 54e remains in engagement 10 with the ratchet and is capable of moving another or several teeth farther before resetting is necessary.

In the use of this device the cigarette is laid on the strip 65 exactly as it would be laid in the 14 depression of any ordinary ash tray. Its inner end extends over the ash receptacle 15f and its burning end will be beyond the thermostatic element 65. However, as the cigarette burns the burning zone will approach the thermostatic element and as the latter becomes heated it will curl upward away from the part 16f. Eventually it reaches the critical angle at which the cigarette slides down until its end contacts the slanting face of the abutment 67. At this point it is 20 stopped and, the heating of the thermostatic strip 65 being greatly reduced, the latter begins to fall back toward the horizontal position.

The abutment 67 is preferably made of a 24 ceramic material, e. g., lava, or other material having low heat conductivity so that it will not extinguish the burning of the cigarette. However, even where the abutment 67 is made of metal this will not ordinarily occur because of 28 the insulating cushion of ash which in almost all cases will cover the burning end and because due to the friction of the cigarette in sliding down the strip 65 the latter contacts only gently with the abutment 67 and is not pressed against it.

The bending of the strip 65 serves the additional function of breaking off any large body of adhering ash from the end of the cigarette which might otherwise prevent the cigarette from dropping to the advanced position.

As will be clear from what has been said above, there would be an advantage in the combination as shown even without the abutment 67 but in that case the cigarette would burn back only once to the thermostat 65 whereupon it would be turned into the receptacle 15f and thereafter would burn itself out in the inclined position.

I have shown and described above the several widely varied designs in order to illustrate 54 the principle of my invention and to bring out the fact that it can be embodied in very many different forms. Obviously, those which have been shown and described are only a few of the innumerable forms which might be given to 60 illustrate the invention.

What I claim is:

1. The combination in an ash tray of a support, adjacent the tray for a smoking article, a pair of rollers forming a part of said support 64 having axles projecting therefrom, a thread with portions turned over each axle in the same rotational direction whereby to frictionally engage said axle to rotate it when said thread is moved, thermostatic means responsive to temperatures 70 near the tray end of said support connected to one end of said thread so as to pull it in response to a rise of temperature and thereby to rotate the roller to feed toward the tray an article supported thereon, and a spring for hold- 76

ing said thread in driving engagement with the axles.

2. The combination in an ash tray of rollers adapted to support a smoking article on their periphery in approximately horizontal position, means secured to the tray for pivotally mounting the rollers, thermostatic motor means close to but substantially beyond the upper part of the roller nearest the center of the tray, and means connecting the rollers to the thermostatic motor means for rotating the rollers so that their uppermost surfaces on which the article rests move toward the central part of the tray by operation of the thermostatic motor means responsive to a temperature increase.

3. A combination as defined in claim 2 which further includes means adapted to restrain the operation of the device for feeding of the smoking article until sufficient force has accumulated to produce a movement adapted to allow recovery of the thermostatic motor means before it is again subjected to heating whereby to produce a reciprocating action of the thermostatic motor means and a step-by-step feeding of the smoking article.

4. The combination as defined in claim 2 in which the means connecting the rollers to the thermostatic motor means is a ratchet device having a spring detent adapted to restrain movement of the device until a sufficient temperature increase of the thermostatic motor means has occurred to move the device at least one full tooth of the ratchet, and the ratio of the ratchet teeth to the roller circumference is such that the movement a distance equal to one full tooth on the ratchet causes a movement of the article sufficient to cause an equivalent reverse movement of the thermostatic motor means by cooling thereof whereby to reset the ratchet.

5. A thermostatic ash tray which comprises a receptacle for ashes, a frame adjacent the receptacle, a plurality of rollers pivotally mounted in the frame, a gear train including gears of approximately equal size and number of teeth connected to said rollers, a thermostat adjacent the upper part of the end roller nearest the receptacle, pawl means connected to said thermostat and engaging one of the gears of said train whereby to drive said gear with a ratchet action when the thermostat is heated, and a detent engaging one of the gears of said train for

restraining movement of the train until a substantial force has accumulated in the thermostat by heating thereof, whereby to give the train a step-by-step movement, and adapted to restrain with a greater force any tendency to movement in the opposite direction.

6. A thermostatic ash tray which comprises a receptacle for ashes, a conveyor means for a smoking article with a burning end, said means being movable to convey said article toward said receptacle in a direction approximately horizontal, a thermostat adjacent an end of said conveyor means and over the receptacle, means connecting said thermostat to said conveyor for moving the article in a direction toward the thermostat, ratchet means for preventing the conveyor from moving the article in the backward direction, and means for restraining the movement of said conveyor means until a sufficient force has been stored in the thermostat by increase of temperature whereby to give the conveyor a full step of a step-by-step movement, the operation at each step being adapted to effect separation between the burning portion of the article and the thermostat sufficient to permit cooling and retraction thereof to reset the ratchet means.

7. A thermostatic ash tray as defined in claim 6 in which the thermostat and ratchet have an operating range of several steps whereby the device may continue to operate normally if a smoking article should be placed with its burning end close to the thermostat after a step movement and before a sufficient cooling period to reset the ratchet.

8. A thermostatic ash tray as defined in claim 6 in which the conveyor means includes a pair of support members having supporting surfaces thereof inclined with respect to one another so that a smoking article thereon will be held by gravity in contact with both, and the ratchet means comprises fine forwardly inclined projections on each of said surfaces, whereby the smoking article may slide readily thereover in one direction but is engaged by said projections when moved in the opposite direction and one of said support members is reciprocable relative to the other, and connected directly to the thermostat to move forward and back upon heating and cooling of the thermostat.

WALDEMAR AYRES.

CERTIFICATE OF CORRECTION.

Patent No. 2,229,953.

January 28, 1941.

WALDEMAR AYRES.

It is hereby certified that error appears in the printed specification of the above numbered patent requiring correction as follows: Page 4, second column, line 14, beginning with the words "In the use" strike out all to and including the word and period "position." in line 53; and that the said Letters Patent should be read with this correction therein that the same may conform to the record of the case in the Patent Office.

Signed and sealed this 27th day of May, A. D. 1941.
